CLAIM

The ornamental design for a headgear assembly for breathing interface, as shown and described.

DESCRIPTION

FIG. 1 is a front, left side perspective view of a headgear assembly for breathing interface.

FIG. 2 is a rear, right side perspective view thereof.

FIG. 3 is a right side view thereof.

FIG. 4 is a rear view thereof.

FIG. 5 is a left side view thereof.

FIG. 6 is a top view thereof.

FIG. 7 is a front view thereof; and,

FIG. 8 is a bottom view thereof.
